Patented Dec. 15, 1914.

UNITED STATES PATENT OFFICE.

JOHN E. WILSON, OF PEN ARGYL, PENNSYLVANIA, ASSIGNOR OF ONE-HALF TO
GEORGE W. GREEN, OF PEN ARGYL, PENNSYLVANIA.

SAW-GUIDE.

1,121,217.

Specification of Letters Patent.

Patented Dec. 15, 1914.

Application filed April 1, 1914. Serial No. 828,855.

To all whom it may concern:

- Be it known that I, JOHN E. WILSON, a citizen of the United States, residing at Pen Argyl, in the county of Northampton and 5 State of Pennsylvania, have invented certain new and useful Improvements in Saw-Guides, of which the following is a specification, reference being had to the accompanying drawings.
- 19 This invention relates to saw guides to be utilized in cutting miters on any angle, either on planes at right angles to the base of the structure or on angles oblique thereto.
- The object of the invention is to provide 15 an implement of this character which shall be simple of construction, highly efficient and durable in use, and in which the parts are so constructed and assembled as to reduce danger of derangement in use to the 20 minimum.

With the above and other objects in view, as will appear as the nature of the invention is better understood, the same consists in the 25 novel construction and arrangement of parts of a saw guide, as will be hereinafter fully described and claimed.

In the accompanying drawings, forming a 30 part of this specification, and in which like characters of reference designate corresponding parts: Figure 1 is a view in side elevation, partly in section of the implement; Fig. 2 is a top plan view with certain portions omitted; Fig. 3 is a view in front elevation of the saw clamp; Fig. 4 is a detached detail view of the frame of the saw clamp; Fig. 5 is a sectional detail view of 35 the combined set screws and bolt used in conjunction with the implement; Fig. 6 is a transverse sectional view taken on the 40 line 6-6 of Fig. 1. Fig. 7 is a detail sectional view of the lower portion of the standard and sleeve that support the saw guide.

Referring to the drawings, 1 designates the base of the structure which is preferably 45 of metal, and is provided along its edges with grooves or channels 2 to be engaged by inturned flanges 3 formed on the base of a gage 4 the latter having combined with it a set screw 5^a by which it may be held securely 50 in position relative to the base. The gage comprises a base 5 and a face plate 6, the latter being disposed at right angles to the long diameter of the base in order to assure the correct cutting of material where the 55 same is to be squared. A second gage 7 is

also provided on the base, to be used in conjunction with that just described, but is devoid of the face plate 6, as this latter gage will be used particularly in holding moldings in position while being mitered.

Rigidly secured adjacent one end of the base is a tubular standard 8, the outer face of which is provided with a longitudinal groove or channel 9 that is designed to be engaged by a lug 10 arranged adjacent to 60 the lower end of a sleeve 11, whereby the latter is held against rotary movement relative to the standard, but will be free to slide vertically thereon. The upper end of the sleeve is reduced to provide a circumferential shoulder 12 upon which rests a split collar 13 threaded into the rear wall of which is a set screw 14, and this screw is hollow to accommodate a plunger 15 having a head 16 between which and the outer wall 65 of the set screw is arranged a coil spring 17, the function of which is normally to hold the plunger in engagement with the sleeve. The collar is held against downward movement upon the sleeve by the shoulder 12, and 70 is provided in register with the inner end of the plunger with a circumferential groove 18 and a series of orifices 19 drilled through the groove and arranged to be engaged by the inner end of the plunger whereby to 75 lock the sleeve at any angle of adjustment, the orifices being provided for setting the implement for cutting standard miters. If, however, it be desired to cut a miter which would not be determined by any one of the 80 orifices 19, then the set screw 14 would come into play, as this could be clamped at a point between any two of the orifices and thus 85 firmly hold the collar against turning.

The collar has projecting from it in parallel relation, two ears 20 and 21 between which is arranged an arm 22 carried by a face plate 23, the scale arm being held pivotally connected with the ears by a bolt 24. In order to permit arcuate movement of the 90 scale arm to allow a miter to be cut at an oblique angle to the vertical axis of the standard 10, the arm is provided with a curved slot 25 through which projects a bolt 26 carried on one end of a thumb nut 27. 105 The upper edge of the arm is provided with a graduated scale as shown in Fig. 2, and this coacts with a master mark 28 scored in the ear 21 and by which the angle of adjustment of the face plate is determined. 110

Pivots connected with the face plate, one adjacent to each end, is a pair of links 29, the upper ends of which are pivotally connected with the frame of the guide. 5 This frame comprises a top plate 30 to which the links are pivoted, two end plates 31, a bottom plate 32, and two angularly disposed plates 33 connecting the bottom and end plates, the structure as a whole 10 being integral, that is to say, formed in one part. The end plates are provided with recesses 34 that are designed to receive one side of the back of a tenon saw, and the other side of which is received between 15 spring clamps 35 secured at their upper ends to the top plate 30 of the clamp, and being free to be swung outward at their lower ends whereby the insertion of the saw may readily be effected and at the same time 20 these clamps will serve to hold the saw properly guided in operation and will prevent wobbling. While primarily the implement is designed more particularly for use in conjunction with a back or tenon saw, it 25 is to be understood that the ordinary hand saw may be used in connection therewith.

It is thought from the foregoing description that the mode of operating the implement will be apparent, but in order that its 30 various uses may be made clear, a description will be given. When the parts of the guide are in the position shown in Fig. 1, the saw will make a cut at right angles to the length of the base, but when an angular 35 cut is desired, the plunger 15 is drawn outward, and the collar turned upon the sleeve until the proper angle has been obtained, whereupon the collar is then locked in this position. When it is desired to make miter 40 cuts in the face of a piece of wood, the frame may be adjusted at any angle by loosening the thumb nut 27 and swinging the frame to the desired angle. Should it be desired to miter lumber of greater width than the base, 45 the gages may be removed.

A very essential feature of the invention resides in the employment of the swinging links 29 by which the frame or head is supported from the collar through the medium 50 of the face plate 23. By the employment of these links the frame and clamps can be thrown out farther over the material, or can be placed close to or moved back therefrom as desired, and it also permits of a 55 higher cut being made when the sleeve has been raised to the limit of its upward movement, on the standard.

From the foregoing description it will be seen that although the improvements herein 60 described are simple in character, that they will be thoroughly efficient for the purposes designed and will coact in the production of a durable and practical form of saw guide.

I claim:

1. In a saw guide, a base, a standard rigid 65 therewith, a sleeve mounted for longitudinal movement on the standard but held from rotary movement relative thereto, a collar rotatably mounted on the sleeve, means for maintaining the collar at any desired ad- 70 justment relative to the sleeve, an arm piv- 75 otally connected for vertical arcuate move- 80 ment with the collar and carrying a face plate, links pivotally connected with the face plate, a frame carried by the upper 85 ends of the links, and resilient saw clamps carried by the frame.

2. A saw guide comprising a standard, a sleeve slidably mounted thereon but held from rotary movement relative thereto, a 80 collar rotatably mounted on the upper por- 85 tion of the sleeve, means for clamping the collar at any desired adjustment relative to the sleeve, ears projecting from the collar, an arm mounted for vertical arcuate move- 90 ment between ears, means for clamping the arm at any adjustment, a face plate carried by the arm, links pivotally connected with the face plate, a frame pivotally connected with the upper ends of the links, and re- 95 silient saw clamps carried by the frame.

3. In a saw guide, a base, a standard pro- 100 jecting therefrom, a sleeve mounted for lon- 105 gitudinal movement on the standard but held from rotary movement relative thereto, a collar rotatably mounted on the sleeve, means for maintaining the collar at any de- 110 sired adjustment relative to the sleeve, an arm pivotally connected for vertical arcuate movement with the collar and carrying a face plate, links pivotally connected with the face plate, a plate carried by the upper 115 ends of the links, and saw guides depending from the plate.

4. In a saw guide, a base, a standard car- 120 ried thereby, a sleeve mounted for longitu- 125 dinal movement on the standard but held from rotary movement relative thereto, a collar rotatably mounted on the sleeve, means for maintaining the collar at any de- 130 sired adjustment relative to the sleeve, an arm pivotally connected for vertical arcuate movement with the collar and carrying a face plate, links pivotally connected with the face plate, a plate pivotally engaged 135 with the links, saw guides depending from the plate, and means coacting with the piv- 140 otal connection between one of the links and the plate for maintaining the plate at any desired adjustment relative to the face plate.

In testimony whereof I hereunto affix my signature in the presence of two witnesses:

JOHN E. WILSON.
